UNITED STATES PATENT OFFICE.

WILLIAM LAMB AND JOHN S. SHIELDS, OF DETROIT, MICHIGAN.

CHECK-VALVE.

1,010,924.

Specification of Letters Patent.

Patented Dec. 5, 1911.

Application filed June 23, 1910. Serial No. 568,529.

To all whom it may concern:

Be it known that we, WILLIAM LAMB and JOHN S. SHIELDS, citizens of the United States, residing at Detroit, in the county of Wayne and State of Michigan, have invented certain new and useful Improvements in Check-Valves; and we do declare the following to be a full, clear, and exact description of the invention, such as will enable others skilled in the art to which it appertains to make and use the same.

This invention relates to improvements in check valves.

The object of the invention is to provide a check valve having means whereby the same is revolved when lifted from its seat by the fluid passing therethrough thus causing the valve to close in a different position each time the same is opened.

With this and other objects in view the invention consists of certain novel features of construction, combination and arrangement of parts as will be more fully described and particularly pointed out in the appended claims.

In the accompanying drawings; Figure 1 is a vertical sectional view through a valve casing showing our improved valve applied thereto. Fig. 2 is a side view of the valve removed; Fig. 3 is an end view of the inner end of the valve.

Referring more particularly to the drawings 1 denotes the upper or disk portion of the valve said portion being of the usual or any suitable construction and is here shown as being provided with a beveled outer edge to engage the seat 2 of the valve casing. On the under side of the disk 1 is formed a series of downwardly projecting spirally disposed blades 3 four of which are shown in the present instance as the preferred number. Any number of blades may, however, be employed.

The blades 3 take the place of the usual guide arms or fingers which guide the valve in its opening and closing movement to cause the same to properly engage its seat

when closing. By arranging the blades 3 in spiral form it will be readily seen that the pressure of the fluid when lifting the valve and passing through the valve casing will engage the radial blades and thereby revolve the valve thus causing the same to seat in a different position each time the valve is closed.

In the upper portion of each of the blades 3 adjacent to the lower side of the disk 1 is formed a slot or elongated passage 4 through which the fluid is permitted to circulate or pass around under the disk thereby causing the pressure or flow of the fluid to more readily revolve the valve as said fluid passes through the seat and casing. By means of our improvement the valve when lifted from its seat is prevented from closing in the same position and thus hammering itself into an uneven shape and causing the same and its seat to wear evenly at all points.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described our invention what we claim is:

1. In a valve, a disk, a series of spirally disposed blades extending from one face thereof, said blades having elongated passages extending transversely therethrough intermediately of their widths adjacent said disks to permit the fluid to circulate through the blades and engage therewith to facilitate the revolving action of the fluid on the blades.

2. In combination with a valve casing and seat thereof, of a disk revolvably mounted in said seat and adapted for vertical movement, a plurality of spirally arranged

blades forming a continuation of the disk, said blades having elongated passages extending transversely therethrough intermediate their width adjacent the disk whereby 5 the fluid is uninterruptedly caused to pass through the valve when unseated and in contact with the entire surface of the blades.

In testimony whereof we have hereunto

set our hands in presence of two subscribing witnesses.

WILLIAM LAMB.
JOHN S. SHIELDS.
